BELT

Irving R. Versoy, New Haven, Conn., assignor to
The Berger Brothers Company, New Haven,
Conn., a corporation of Connecticut

Application April 17, 1947, Serial No. 742,111

6 Claims. (Cl. 2-43)

1

This invention relates to a belt or support, and more particularly to a garment of this nature adapted to be worn for the support of the abdomen and back.

The garment illustrated is particularly desirable for fleshy men, and more particularly for those with more or less soft flabby flesh which needs to be confined and supported. It is desirable that such a support or girdle should be so constructed that it is sufficiently flexible to allow great freedom of movement and to be comfortable to the wearer, while, at the same time, confining the flesh and offering support to the abdominal walls and also to the back, if necessary.

In some instances, garments which have been designed for this purpose occasion considerable discomfort to the wearer and interfere with his freedom of movement in that, if they are sufficiently stiff and strong to have the required supporting and confining functions, they are not sufficiently flexible.

It is the object of the present invention, therefore, to provide a garment of this kind which will fit the above requirements; the garment being provided with a rear or back section of relatively large size to contact the back of the wearer over a considerable area, and a front section to overlie the abdomen, and particularly the lower part thereof, so as to give the required support to the said fleshy portions of the body.

A further object of the invention is to provide a belt or girdle of the character described provided with front and rear sections connected by separate, but usually overlapping, tabs, so that, while the front and back sections or panels will have the required confining action, the connecting tabs will permit freedom of movement at the sides between said sections.

To these and other ends the invention consists in the novel features and combinations of parts to be hereinafter described and claimed.

In the accompanying drawings:

Fig. 1 is a front elevational view of a belt or girdle embodying my invention;

Fig. 2 is a side view of the same, showing the manner in which the front and back sections are connected;

Fig. 3 is a front elevational view of a belt or girdle of somewhat modified form;

Fig. 4 is a partial side view of the belt shown in Fig. 3;

Fig. 5 is an inside elevational view of the front panel of the garment shown in Figs. 3 and 4;

2

Fig. 6 is a sectional view of the back section of the garment on line 6-6 of Fig. 4; and

Fig. 7 is a sectional view of the front section of the garment on line 7-7 of Fig. 5.

As illustrated in the drawings, I have shown a belt or girdle comprising a back section 10 and a front section 11. The back section is provided with a plurality of vertically extending stiffening, but flexible, stays or steels 12, four in number, as shown, although this may be varied as desired. The back section or panel 10 is continuous between the outer stays and will preferably be formed of non-elastic fabric, whereby this section will contact the back of the wearer over a wide area, so that the strain or pressure will be distributed over this area.

The front section 11 of the garment, as illustrated, is relatively small as compared to the back section and is provided with generally vertically extending flexible stays or stiffening members 13. As illustrated, there are three of such members, although the number may be varied if desired; those at the side edges of the front section diverging slightly. This front section or panel is likewise preferably formed of non-elastic fabric material, and is continuous, that is, devoid of openings between the two outer stays or steels 13.

The manner in which the front and back sections are connected will now be described.

At each side edge of the front section, tabs 14 and 15 are provided, these tabs extending from the outer stay members 13. The adjacent edges of the tabs diverge, and the tabs themselves are superimposed over a wing member 16, which fills the angle between the tabs and makes a substantially continuous side section at each side of the front panel, this side section being reinforced by the tabs.

At each side of the rear section are provided 40 forwardly extending tabs 17 and 18, these tabs being tapered in width toward the front, so that their smaller forward free ends are spaced apart to some extent. As the garment is worn in a relatively low position on the body, the hip bones of the wearer are designed to lie in the space between the forward ends of the tabs 17 and 18, and thus these bones are not confined, and the pressure which would otherwise be placed thereon is relieved.

The sections are connected by adjustable and readily detachable straps as will now be explained. Loops 19 are secured to the front section, and through these loops are passed straps 20 having adjusting buckles 21 thereon. These straps are passed through loops 22 which are

designed to be swivelly engaged with buttons 23 secured to the adjacent end portions of the tabs 17 and 18. After being passed through the loops 22, the ends of the straps are brought back to the front section of the garment and secured along the upper and lower edges thereof. Diverging straps 24 may extend from the buttons 23 to reinforcements 25 provided vertically on the tabs 17 and 18, so as to distribute the pull or strain upon the buttons 23 over the width of the tabs 17 and 18 and, likewise, over the width of the back section 10.

The connection between the loops 22 and the buttons 23, while being readily detachable, also provides a swivelling action, so that movement of one section of the garment with respect to the other is permitted, while, at the same time, the straps 20 will at all times lie flat and not tend to curl or pull at one edge. This is particularly desirable when the wearer changes his position, as when changing from a sitting to a standing position, or vice versa.

In Figs. 3 to 7 of the drawings, I have shown a modified form of support in which a supplemental section or extension is provided to co-operate with the front panel of the garment. In this garment, the rear section 10 and front section 11 are substantially the same as has been previously described in connection with the garment shown in Figs. 1 and 2. In this case, however, the rear section is provided with a plurality of forwardly extending tabs 27, 28, and 29, these tabs tapering toward their free edges, but having their adjacent edges in overlapping relation, as shown in Fig. 4, while their free ends are in spaced relation so as not to confine the body of the wearer to an excessive extent at the sides thereof. The front and back sections are connected by means of the straps 20 in the same manner as previously described in connection with the garment shown in Figs. 1 and 2.

A supplemental front section or extension 30 is provided, which section, at its lower portion, overlaps the front panel 11. As shown, the lower portion of the section 30 extends within and lies beneath the front panel, while the upper portion of the section 30 extends above the front panel and offers support for the front of the body of the wearer over an extended vertical area.

This extension or supplemental section 30 may be entirely free or entirely disconnected from the front panel 11. As shown, however, it is connected to the front panel at two relatively widely spaced points 31 and 32, but otherwise is left free. The connections 31 and 32 prevent separation of the section 30 from the front panel 11 and hold these two parts in proper assembled position, but, at the same time, allow a considerable freedom of movement between the sections. That is, between the points 31 and 32 the section 30 may telescope within the section 11 or withdraw therefrom to a considerable extent when the wearer, for example, changes from a sitting to a standing position, or bends forwardly or rearwardly as the case may be. Thus, the belt may be conveniently worn by a man playing golf or doing other forms of exercise without undue restraint over the movements of the body.

To the supplemental section or extension 30 are connected straps 33 in a manner similar to the connection of the straps 20 with the main front section 11, which straps 33 are provided

with loops 34 swivelly engaging the buttons 35 on the upper tabs 29 of the rear section.

As shown in Fig. 6, the rear section 10 of the garment, whether that shown in Figs. 1 and 2, or whether that shown in Figs. 3 to 5, is shaped or formed, as shown at 36, to fit over the hips of the wearer and thus prevent any tendency of the garment to move upwardly. The sectional view of Fig. 7 illustrates the overlapping relation of the supplemental section 30 and the front panel 11, and, as stated, considerable freedom is allowed for these two sections to telescope or slide one relatively to the other, so that there is no tendency of the garment to unduly restrain the body of the wearer during bending and other movements.

The supplemental section 30 is also provided with generally vertically extending stays 38 and 39, which, while flexible, nevertheless, give some stiffness or rigidity to this section in a vertical direction. Thus, this section of the garment will to some extent, and particularly when outward pressure is exerted on the upper edge thereof, pivot or swing about the upper edge of the front panel 11, so as to cause the lower edge of the supplemental section 30 to move inwardly and thus press inwardly on this portion of the abdomen.

While I have shown and described some preferred embodiments of my invention, it will be understood that it is not to be limited to all of the details shown, but is capable of modification and variation within the spirit of the invention and within the scope of the claims.

What I claim is:

1. A supporting garment or belt comprising a central front section having a plurality of spaced stiffening members therein extending generally vertically thereof, a plurality of tabs secured to the side edges of said section to extend laterally therefrom, a back section the lower portion of which is shaped to conform to the upper portion of the hips of the wearer, a series of tabs extending from each side edge of said back section, straps secured to the tabs of one section and removably secured to the tabs of the other section by a swivel connection, each of said straps being adjustable independently of the other so as to apply tension to one set of tabs independently of the other, one tab on each side of the back section being adapted to cover that portion of the body between the ribs and the hip portion of the wearer and said front section being of less height vertically than the back section.

2. A supporting garment comprising a front section and a back section, said sections being of inelastic material and each having generally vertical stiffening members therein, a plurality of relatively wide tabs secured to each side edge of the back section to extend toward the front section, strap means secured to said tabs and connecting them individually to the front section and adapted to apply tension on the tabs, one tab on each side of the back section being adapted to cover that portion of the body between the ribs and the hip portion, an extension member attached to the upper portion of the front section and projecting upwardly therefrom, and adjustable means connecting said extension member to the back section of the garment.

3. A supporting garment comprising a front section and a back section, said sections being

of inelastic material and each having generally vertical stiffening members therein, a plurality of relatively wide tabs secured to each side edge of the back section to extend toward the front section, strap means secured to said tabs and connecting them individually to the front section and adapted to apply tension on the tabs, one tab on each side of the back section being adapted to cover that portion of the body between the ribs and the hip portion, an extension member attached to the upper portion of the front section and projecting upwardly therefrom, adjustable means connecting said extension member to the back section of the garment, and the lower portion of said extension member extending below and within the front section.

4. A supporting garment comprising a front section and a back section, said sections being of inelastic material and each having generally vertical stiffening members therein, a plurality of relatively wide tabs secured to each side edge of the back section to extend toward the front section, strap means secured to said tabs and connecting them individually to the front section and adapted to apply tension on the tabs, one tab on each side of the back section being adapted to cover that portion of the body between the ribs and the hip portion, an extension member attached to the upper portion of the front section and projecting upwardly therefrom, adjustable means connecting said extension member to the back section of the garment, and the lower portion of said extension member permitting limited movement thereof with respect to the front section when the garment is worn.

5. A supporting garment comprising a front section and a back section, said sections being of inelastic material and each having generally vertical stiffening members therein, a plurality of relatively wide tabs secured to each side edge of the back section to extend toward the front section, strap means secured to said tabs and connecting them individually to the front section and adapted to apply tension on the tabs,

one tab on each side of the back section being adapted to cover that portion of the body between the ribs and the hip portion, an extension member secured at widely spaced points to the upper portion of the front section adjacent the upper edge thereof and being otherwise free for limited movement between said points with respect to said section, and means adjustably securing said extension member to the back section of the garment.

6. A supporting garment comprising a front section and a back section, said sections being of inelastic material and each having generally vertical stiffening members therein, a plurality of relatively wide tabs secured to each side edge of the back section to extend toward the front section, strap means secured to said tabs and connecting them individually to the front section and adapted to apply tension on the tabs, one tab on each side of the back section being adapted to cover that portion of the body between the ribs and the hip portion, an extension member secured at widely spaced points to the upper portion of the front section adjacent the upper edge thereof and being otherwise free for limited movement between said points with respect to said section, means adjustably securing said extension member to the back section of the garment, and said extension member extending below the upper edge of the front section and being adapted for telescoping movements within the front section when the garment is worn.
